UNITED STATES PATENT OFFICE.

JOSEPH W. PARKIN, OF PHILADELPHIA, PENNSYLVANIA.

CARBURETER.

1,183,587.

Specification of Letters Patent. Patented May 16, 1916.

Application filed December 16, 1914. Serial No. 877,474.

To all whom it may concern:

Be it known that I, JOSEPH W. PARKIN, a citizen of the United States, residing at Philadelphia, in the county of Philadelphia and State of Pennsylvania, have invented 5 certain new and useful Improvements in Carburetors, of which the following is a specification.

The object of my invention is to provide 10 a carburetor of novel, simple and efficient construction, having provision, first, whereby the oil may be thoroughly vaporized in the carbureting chamber, secondly, whereby the oil may be admitted through one 15 port when the engine is running idle and through another port when the engine is running with the load on, one port being closed while the other is open so that the admission of oil through the two ports may 20 be controlled and regulated independently of each other, and, thirdly, whereby various novel advantages are gained.

With this object in view, my invented device consists of the elements and the combinations of them hereinafter fully described and claimed.

In the accompanying drawings, illustrating my invention: Figure 1 is a vertical section approximately central of my improved 30 carburetor showing the air controlling valve in the open position. Fig. 2 is a similar view of a portion thereof, but showing the air controlling valve in the closed position. Fig. 3 is a transverse vertical section of the device taken approximately on the line 3--3 of Fig. 2, certain of the internal parts being shown in elevation. Fig. 4 is a side elevation of a portion of the carburetor. Fig. 5 is an enlarged vertical section of the oil 35 supply pipe and the controlling valve therefor together with an associated baffle sleeve for facilitating the vaporization of the oil. Figs. 6 and 7 are similar views of modified forms thereof. Fig. 8 is an enlarged section taken approximately on the line 8--8 of Fig. 2 of the conduit for supplying the oil while the engine is running idle.

Referring to the drawings, 9 designates a 40 casing which incloses a valve chamber for the air and vaporized oil and having an inlet opening 10 and an outlet opening 11. The upper portion of the casing 9 extends upwardly in flaring pipe like form 12, the upper end of which is provided with a flange 13 by means of which the carburetor may be secured to the inlet passage way of the

engine to which the explosive mixture is drawn.

Adjacent to the casing 9 is a casing 14 inclosing an oil chamber or reservoir 15, and below the casing 9 is a casing 16 inclosing an air or supply chamber 17 which is in communication by means of the inlet 10 with the interior of the casing 9, and the casing 16 is also provided with an integral horizontally-extending portion 18 forming an inlet pipe for the supply of the air to the carburetor. Arranged within the chamber 17 is a hollow standard 19 the interior 20 of which forms a chamber for the supply of oil to the vertically arranged valve pipe 21 which is supported in the hollow standard 19 in a manner to be presently explained. The chamber 20 is in communication with the lower portion of the oil chamber 15 by means of a port 22 extending therebetween. The lower end of the chamber 20 is closed by means of a suitable threaded plug 23. The interior of the chamber 20 is threaded throughout its vertical 25 extension, except for a small portion at the top thereof, where it is provided with a shoulder 24 adapted for the reception of an enlarged head or collar 25 which is secured to and carried by the lower end of the oil pipe 21. The collar 25 is provided with a seat 26 which fits a vertical slot 27 cut in the interior threaded portion of the standard 19 to prevent improper rotation of the pipe 21 with respect to the standard 19. An externally threaded collar 28 serves to maintain the collar 25 and consequently the pipe 21 in the proper position in the upper end of the standard 19.

The upper end of the pipe 21 extends into 30 the carbureting chamber inclosed by the casing 9 and is entirely closed near its upper end by a fixed partition 30 (see Fig. 5). The pipe 21 is provided with a port 31 below the partition 30 for the discharge of oil into the 35 valve chamber. The port 31 is adapted to be closed or partially closed or left entirely open by a valve head 32 comprising a tubular body closed at its upper end and surrounding and slidably fitted to the upper end 40 of the pipe 21. The valve head 32 is forced normally upward to open the passage way 31 by a spring 33 inclosed by the head 32, one end of said spring bearing against the partition 30 and the other end against the 45 interior of the cap or head 32. The valve head 32 is adapted to be depressed against

the action of the spring 33 and permitted to be raised by the spring to close or partially close and open the passageway 31 by means of devices and for a purpose which will be 5 hereinafter explained. Surrounding the pipe 21 and port 31 therein in spaced relation thereto is a baffle sleeve 34 which extends downwardly a distance below the port 31 to provide an annular space 35, the baffle 10 sleeve 34 being open at its bottom and closed at its top, as shown. The sleeve 34 is provided with a series of perforations 36, preferably located above the port 31. The baffle sleeve 34 communicates with the carbureting 15 chamber through the open bottom of the sleeve and the perforations 36, so that when air is drawn through the carbureting chamber, oil will be drawn from the port 31 and caused to strike the baffle sleeve 34 and after- 20 ward pass to the carbureting chamber through the perforations 36 and the open bottom of the sleeve, thus atomizing the oil or breaking it up into finely divided particles as it enters the carbureting chamber. 25 The valve for controlling the flow of air through the carbureter comprises a cylindrical body 37 mounted within the casing 9 and fitted to turn on a horizontal axis therein. The said cylindrical body 37 is provided with a passage way 38 extending therethrough transversely to its turning axis. The passage way 38 forms a part of the carbureting chamber inclosed by the casing 9 and the passage way 38 forms a part of the 35 carbureting chamber inclosed by the casing 9 and the passage way 38 is substantially the same in diameter as the vertically extending inlet opening 10 and outlet opening 11 of the valve chamber so that the valve 37 may 40 be turned to the full open position shown in Fig. 1 to bring the passage way into registry with the openings 10 and 11 to permit a large volume of air to be drawn therethrough; and so that the valve 37 may be 45 turned to the position in Fig. 2 or to any position intermediate the position shown in Figs. 1 and 2 to reduce the volume of air passing through the carbureting chamber, and thereby regulate the volume of air in accordance 50 with the speed of the engine. The valve body 37 is provided at one end with a solid stem 39 and at its other end with a tubular stem 40 extending outwardly at their respective ends through the end walls 55 41 and 42, respectively of the casing 9. The outer end of the tubular stem 40 has an arm 43 adjustably secured thereto and by means of which the valve 37 may be turned. 60 When the valve 37 is moved to the position shown in Fig. 1 the valve head 32 is simultaneously moved under the tension of the spring 33 to open the passage way 31 and when the valve 37 is moved to the position shown in Fig. 2 the valve head 32 is moved 65 to close the passage way 31 and for this pur-

pose there is provided the following mechanism: Extending axially through the tubular valve stem 40 is a shaft 44 the inner end of which is provided with a cylindrical projection 45 extending parallel to and out of alignment with the axis of the shaft 44. The top of the valve head 32 is forced into constant contact with this eccentric projection 45 by the spring 33 and the projection 45 is so arranged that when the shaft 70 44 and stem 40 are turned as a unit the valves 37 and 32 may be simultaneously moved from the position shown in Fig. 1 to the position shown in Fig. 2 and back again. The outer end of the shaft 44 extends beyond the tubular stem 40 and has an arm 46 fixed thereto which arm lies adjacent the arm 43 which is carried by the stem 40. The two arms 43 and 46 are secured together by means of a screw 47 extending through a slot 48 in the arm 46 and threaded into the arm 43 so that the stem 40 and shaft 44 will move as a unit when the arm 43 is operated. The slot 48 is so arranged that the arm 46 and shaft 44 may be adjusted about the axis 85 of the stem 40 by loosening the screw 47 and thereby permitting the position of the projection 45 with respect to the valve 37 to be changed and thereby permitting the timing of the operation of the valve 32 with respect to the movement of the valve 37 to be nicely regulated. The movement of the arm 43 and the valve 37 in one direction to the position of the valve shown in Fig. 1 is limited by a stop 49 projecting from the end wall 42 of the casing 9 and adapted to engage a projection 50 carried by the arm 43; and the movement of the arm 43 and valve 37 in the reversed direction to or near the position shown in Fig. 2 is limited by a similar stop 100 51 likewise carried by the end wall 42 of the casing 9.

The oil is supplied to the chamber 15 through an inlet 52 which extends centrally through a nipple 53 which extends from the lower part of the casing 11. The nipple 53 is externally threaded for a portion of its length so as to be engaged by the hollow end 54 of a hexagon head plug 55, the hollow portion of which is provided with 110 screened ports 56 to permit the oil to enter the interior of the hollow end 54 from the chamber 57 which is mounted on a smooth portion of the nipple 53 and seated against the lower surface of the casing 11 being held in place theron by means of the plug 55 which has its hollow portion 54 in threaded engagement with the nipple 53 as before stated. The casing 58 it will be noted is capable of being swiveled so as to permit its inlet nipple 59 to be brought to any desired circumferential position for the ready attachment of the pipe from which the oil is initially supplied. A bushing 60 is threaded into the upper interior end of the aper- 120 130

ture 52 and provides a seat for a needle valve 61 formed by sharpening the end of a stem 62 which extends vertically upward through the center of the oil chamber 15 and is guided at its upper end in the cap 63 which is mounted on the top of the casing 14. The valve stem 62 has secured thereto a grooved collar 64 which is engaged by the ball ends 65 of levers 66 which are pivoted in brackets 67 carried by the cap 63. The outer end of the levers 66 is provided with ball weights 68 which rest on the top surface of a hollow float 69 which surrounds the valve stem 62 and rises and falls with the level of the oil contained within the chamber 15. It will be seen that the arrangement is such that when the oil level falls the float will drop and consequently the ball 68 will fall operating the levers 66 on their respective pivots and through the engagement of the ball ends 65 on their inner ends will cause the stem 62 to be raised and thereby raising the valve 61 on its seat and permitting more oil to flow into the chamber 15 to restore the same to the proper level. The level of the oil within the chamber 15 and consequently within the pipe 21 is thus maintained just below the discharge opening or passage way 31 by the automatic action of the float 69 in opening the valve 61 when the oil falls below said level, and closing said valve 61 when the oil reaches said level.

The upper portion of the oil supply pipe 21 extends into the passage way 38 and a slot 70 is cut in the wall 71 of the valve body 37 to receive the pipe 21 and its surrounding sleeve 34 when the valve 37 is moved to the position shown in Fig. 2, the slot 70 being sufficiently large to permit the air to pass therethrough when the parts are in this position. The wall 72 of the valve body 37 has a slot or opening 73 cut therein to permit air to pass from the passage way 38 and through the outlet opening 11 when the parts are in the position shown in Fig. 2. To vary the opening provided in the slot 70 between the passage way 38 and the air inlet 10 there is provided a pin 74 slidably fitted to an opening in the wall of the casing 9 and held in place by a set screw 75 and extending into the slot 70 and adjustable into and from the same.

When the engine is running idle or without a load the valves 37 and 32 are in the position shown in Fig. 2, the passage way 31 being closed and the slots or openings 70 and 73 permitting sufficient air to be drawn into the engine for the required mixture for slow speed. The slot or opening 70 may be varied by adjusting the pin 74 to regulate the amount of air supplied in accordance with the requirements of the engine and thus running without a load. To provide

ditions there is provided a by-pass channel or port 76 extending from the interior of the oil chamber 15 below the normal level of the oil contained therein to the inner surface of the valve casing 9 at such a point as 70 to be closed by the valve body 37 when the same is in the position shown in Fig. 1, and to be exposed to and communicate with the carbureting chamber when the valve body 37 is in the position shown in Fig. 2. To 75 regulate the amount of oil supplied when the same is being drawn through the port 76 there is provided a regulating screw 77 having a pointed end 78 which extends a regulatable distance into the port 76 as 80 clearly shown in Fig. 8 of the drawings.

In order that carbureters having the same general dimensions may be used in connection with different engines requiring air inlet passage ways of different cross-sectional areas, I provide the upper end of the sleeve 34 with a removable collar 79 which is forced on to the sleeve 34 and held in place thereon by frictional engagement therewith. A sleeve 79 of any suitable diameter may be 90 applied to a particular carbureter according to the requirements of the particular engine on which the carbureter is used. The sleeve 79 not only performs the function previously mentioned but it also serves as a baffle in the 95 carbureting chamber and thereby assists in the mixing of the vaporized oil and air.

In the modification shown in Fig. 6, I provide an additional baffle sleeve 80 which surrounds the sleeve 34 in spaced relation thereto and has an open bottom and a series of perforations 81, affording communication between the carbureting chamber and the interior of the baffle sleeve 80. The upper end of the sleeve 80 is secured to the valve 100 head 32, and the lower end of the sleeve 80 is connected by arms 82 to a collar which is 105 slideable on the pipe 21. In lieu of the spring 33, a spring 84 is provided which encircles the pipe 21 between the collars 25 and 110 83 and forces the valve head 32 upwardly.

In the modification shown in Fig. 7, I provide two additional baffle sleeves 85 and 86. The sleeve 85 surrounds the sleeve 34 in spaced relation thereto and the sleeve 86 surrounds the sleeve 85 in spaced relation to the latter. The upper ends of the sleeves 85 and 86 are secured to the valve head 32. The sleeve 85 is provided with a series of perforations 87, affording communication between the 120 two additional sleeves 85 and 86, and the sleeve 86 is provided with a series of perforations 88, affording communication between the carbureting chamber and the interior of the outer sleeve 86. The bottoms 125 of the spaces between the sleeves 85 and 86 are closed by a ring 89 which is connected by arms 90 to a collar 91 which is slideable on the pipe 21. The valve head 32 is forced upwardly in this construction, similar to 130

the construction shown in Fig. 6, by a spring 92 encircling the pipe 21 between the collars 25 and 91.

I claim:

- 5 1. In a carbureter, a casing inclosing a carbureting chamber having an outlet opening and an air inlet opening, an oil supply pipe extending into the chamber and having an oil discharge port therein, a valve head slidably mounted on said pipe and movable to control said port, a baffle sleeve carried by said valve head and having a closed upper end and an open lower end and surrounding said pipe and the port therein in spaced relation thereto, and in spaced relation to the casing, affording a passage way between said openings exteriorly of the sleeve, the interior of said sleeve communicating with said chamber, and 20 means operative to move said valve head.
2. In a carbureter, a casing inclosing a carbureting chamber having an outlet opening and an air inlet opening, an oil supply pipe extending into the chamber and having an oil discharge port therein, a valve head slidably mounted on said pipe and movable to control said port, a baffle sleeve carried by said valve head and surrounding said pipe and the port therein in spaced relation thereto, and in spaced relation to the casing, affording a passage way between said openings exteriorly of the sleeve, said sleeve having a series of perforations therein affording communication between said chamber and the interior of the sleeve, and means operative to move said valve head.
3. In a carbureter, a casing inclosing a carbureting chamber having an outlet opening and an air inlet opening, an oil supply pipe extending into the chamber and having an oil discharge port therein, a valve head slidably mounted on said pipe and movable to control said port, a baffle sleeve carried by said valve head and surrounding said pipe and the port therein in spaced relation thereto, and in spaced relation to the casing, affording a passage way between said openings exteriorly of the sleeve, said sleeve being closed at its upper end and having an open bottom and a series of perforations affording communication between said chamber and the interior of the sleeve, and means operative to move said valve head.
4. In a carbureter, a casing inclosing a carbureting chamber having an outlet opening and an air inlet opening, an oil supply pipe extending into the chamber and having an oil discharge port therein, a valve head slidably mounted on said pipe and movable to control said port, a baffle sleeve carried by said valve head and surrounding said pipe and the port therein in spaced

relation thereto, a second baffle sleeve carried by said valve head and surrounding the first named sleeve in spaced relation thereto, the interior of the first named sleeve communicating with the interior of the second named sleeve, and the interior of the second named sleeve communicating with said chamber, and means operative to 70 move said valve head.

5. In a carbureter, a casing inclosing a carbureting chamber having an outlet opening and an air inlet opening, an oil supply pipe extending into the chamber and having an oil discharge port therein, a valve head slidably mounted on said pipe and movable to control said port, a baffle sleeve carried by said valve head and surrounding said pipe and the port therein in spaced relation thereto, a second baffle sleeve carried by said valve head and surrounding the first named sleeve in spaced relation thereto, the first named sleeve having a series of perforations therein affording communication between said sleeves, and the second named sleeve having a series of perforations therein affording communication between it and said chamber, and means operative to move said valve head.

6. In a carbureter, a source of oil supply, a casing inclosing a carbureting chamber having a mixture outlet opening and an air inlet opening and an oil port communicating with said source of supply and discharging into said chamber, an oil supply pipe communicating with said source of supply and extending into the chamber and having an oil discharge port therein, a valve controlling the supply of oil through said pipe, a valve controlling said outlet opening and movable to open and close the oil port in said casing, and means operative to move said valves.

7. In a carbureter, a casing inclosing a carbureting chamber having a mixture outlet opening and an air inlet opening and an oil port discharging into said chamber, an oil supply pipe extending into the chamber and having an oil discharge port therein, a valve movable to open and close the oil port in said pipe, a valve controlling said outlet opening and movable to open and close the oil port in said casing, and means operative to simultaneously move said valves, the oil port in said casing being closed when the oil port in said pipe is open.

In testimony whereof I affix my signature in presence of two witnesses.

JOSEPH W. PARKIN.
